[57] CLAIM

The ornamental design for a combined tape player, disc player and radio receiver, as shown and described.

DESCRIPTION

FIG. 1 is a perspective view of a combined tape player, disc player and radio receiver showing my new design; FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and

FIG. 7 is a rear elevational view thereof.

FIG. 8 is another perspective view thereof, wherein the cover portions are in the open position; and,

FIG. 9 is yet another perspective view thereof, wherein the handle and antenna portions are in the standing position.

FIGS. 1, 8 and 9 are on a reduced scale.

The surfaces or portions of the combined tape player, disc player and radio receiver not shown in the drawing or described in the specification form no part of the claimed design.
